(57) **CLAIM**

The ornamental design for a distribution controller for air conditioner, as shown and described.

DESCRIPTION

FIG. 1. is a first perspective view of the front, right, and top sides of a distribution controller for air conditioner showing our new design;

FIG. 2. is a second perspective view of the front, left, and bottom sides thereof;

FIG. 3. is a front view thereof;

FIG. 4. is a rear view thereof;

FIG. 5. is a left side view thereof;

FIG. 6. is a right side view thereof;

FIG. 7. is a top plan view thereof; and,

FIG. 8. is a bottom plan view thereof.

The broken lines shown represent unclaimed subject matter of the distribution controller for air conditioner and form no part of the claimed design.
